UNITED STATES PATENT OFFICE

2,582,765

DOOR AND WINDOW TRIM

Lewis J. Brew, Rochester, N. Y.

Application August 4, 1948, Serial No. 42,389

7 Claims. (Cl. 189—46)

1

The present invention relates to the trim used in buildings, such as door and window casings. In a more particular aspect the invention relates to metal trim for doors and windows.

The conventional type metal trim is of one-piece construction. It is made at the factory and so shipped to the job. Conventional metal trim has, therefore, to be placed in the window and door openings before the walls are plastered and painted. It has to be erected, while heavy work is still being done on the building. It has to stand in place while wheelbarrows are being rolled back and forth and while scaffolding and other erection equipment is being moved to and fro. It is very liable, therefore, to be marred or dented.

Moreover, when it comes time to plaster the walls, the plasterer has to plaster up to the trim, which naturally handicaps him. He is not able to make free-swinging strokes; and as a result has difficulty in producing a plane surface. Furthermore, he is always confronted with the possibility of smearing the trim. Similar difficulties are encountered in painting the walls around the trim. All this adds to the time required for plastering and painting walls where metal trim is used and increases the cost of these jobs.

A further disadvantage of the conventional type metal trim is that it cannot be removed from a partition wall without wrecking the wall around the door or window opening in which the trim is mounted.

One object of the invention is to provide an improved type of metal trim which can be erected after plastering and painting are finished. This prevents the trim from being damaged during erection of the building, materially reduces the cost of plastering and painting on a job where metal trim is used, and simplifies the work. It eliminates entirely the necessity for cleaning the trim after plastering and painting of the adjacent walls are completed.

Another object of the invention is to provide metal trim which can be shipped in knockdown form and assembled at the erection site by relatively unskilled labor.

A further object of the invention is to provide metal trim which can be removed and salvaged one hundred per cent, without in any way marring or defacing the walls adjacent the opening in which the trim is mounted.

Still another object of the invention is to provide metal trim for door openings which can at any time easily be taken down and reversed in the door opening to permit reversal of the direction of swing of the door.

A further object of the invention is to provide a knockdown type of trim which is made of a minimum number of parts and is inexpensive.

A still further object of the invention is to

2

provide knockdown, easily assemblable trim in which connections between the parts will be concealed when the trim is in place and which will look like conventional one-piece trim when erected.

Other objects of the invention will be apparent hereinafter from the specification and from the recital of the appended claims.

In the drawings:

10 Fig. 1 is a perspective view of a portion of a wall having a door-opening therein in which is mounted a door casing made in accordance with the present invention.

15 Fig. 2 is a fragmentary side elevation of this door casing;

Fig. 3 is a section through the casing taken on the line 3—3 of Fig. 4;

20 Fig. 4 is a view of the casing looking from the right in Fig. 2, parts being broken away better to show the construction;

Fig. 5 is a detail view on a greatly enlarged scale, showing in perspective the reinforcing members for the two side parts of the casing;

25 Fig. 6 is a perspective view of one of the foot pieces for the casing;

Fig. 7 is a fragmentary perspective view looking at the back of the top door-stop or covering strip of the casing;

30 Fig. 8 is a perspective view looking at the front side of one of the side door-stop or covering strips of the casing;

Fig. 9 is a sectional view, similar to Fig. 3, showing a door casing constructed according to a modified form of the present invention; and

35 Fig. 10 is a fragmentary elevation with parts broken away, somewhat like Fig. 4, but showing this modified form of the invention.

A door casing constructed according to the present invention is made with two main sections 40 and with strips which cover the adjoining ends of the main sections. The two main sections for convenience may be called outside and inside sections, respectively. One section seats against one side and the other against the other side of the 45 partition wall in which the door opening is provided and the two sections are drawn together to clamp the casing in the opening.

In Figs. 1 to 4 inclusive the two main sections are denoted at 20 and 21, respectively. These sections are each U-shaped; and each comprises a pair of parallel side rails 22 and a connecting top rail 24. The side and top rails of each section are mitered at their adjoining ends and welded together so that each section can be handled as 55 one piece.

The rails may obviously be rolled or stamped to any desired shape in cross-section to suit the style of architecture selected. In the embodiment shown, each rail comprises a flat side 25 from one end of which projects outwardly a terminal strip

26 and from the other end of which projects inwardly the side wall 27. From the side wall 27 is bent inwardly a flange 28. The flanges 28 of the top and side rails of the two sections are adapted to abut against opposite faces 30 and 31 of the partition wall in which the casing is to be mounted.

Each rail is reinforced at spaced points along its length by reinforcing strips such as denoted at 35 (Figs. 3, 4 and 5). These reinforcing strips comprise strap portions 36 and legs 37 and 38 which project in opposite directions from the strap portions 36. Each leg 37 has an abutment strip 39 projecting at right angles from it in one direction; and each strap portion 36 has a tongue 40 stamped out of it and bent to project at right angles to the leg 37 of the reinforcing strip in the opposite direction from abutment strip 39. Each tongue 40 has an elongated slot 41 formed therein.

The legs 38 of the reinforcing strips are bent to conform to the shape of the side walls of the frame sections as shown clearly in Fig. 3, and are spot-welded to the insides of these side walls. The terminal portions 42 of the legs 38 are also preferably bent slightly inwardly and spot-welded to the insides of flanges 28 of the frame sections. The abutment strips 39 are spot-welded to the insides of the sides 25 of the frame sections. A very rigid structure is thereby provided. All spot-welding is done, of course, in the factory when the frame sections are being manufactured.

The U-shaped sections 20 and 21 are ordinarily painted at the factory and shipped in cartons to the job. After the partition walls have been plastered and painted and all the heavy work on the building is completed, the novel door or window framing of this invention can be placed. To do this the workman may drive nails 43 through the slots 41 in the tongues of the reinforcing strips 35 into the studding 45 (Fig. 3) to hold each frame section in place.

After the two frame sections 20 and 21 are so held, he will pull them together so that their flanges 28 will contact and abut against opposite sides of the partition wall of the building. Various means may be employed for this purpose. In the embodiment of the invention shown in Figs. 2 to 5 inclusive, bolts 50 and butterfly nuts 51 are provided for effecting the clamping movement. The bolts 50 have right-hand and left-hand threads, respectively, at opposite ends. The leg 37 of each reinforcing strip 35 has a notch 44 (Fig. 5) in it. To pull the sections 20 and 21 together and clamp them to the partition, the workman drops a bolt 50 in the notches 44 of registering reinforcing strips 35 of the sections 20 and 21, puts butterfly nuts 51 on opposite ends of the bolt and rotates the bolt. The butterfly nuts are held against rotation by engagement with the reinforcing strips. The bolts 50 may have polygonal center portions for easy grip by a wrench. The slots 41 in the tongues 40 of the registering reinforcing strips permit adjustment of the frame sections while they are held to the partition by the nails 43. One man can, therefore, very easily assemble the frame in a door or window.

Ordinarily clamping bolts 50 and butterfly nuts 51 need only be used in the reinforcing strips attached to the side rails of the frame sections to pull the frame sections together. The top rail of each frame section is welded to the side rails thereof so that when the sides of the frame

sections are pulled together, the tops of the sections will be pulled together also. If desired, however, bolts 50 and butterfly nuts 51 may be used between the reinforcing strips 35 of top rails as well as of side rails. All the reinforcing strips are made alike for convenience in manufacture, and the reinforcing strips welded to the top rails of the two sections of the frame will have notches 44 in them just like the reinforcing strips welded to the side rails of the two frame sections.

Obviously, instead of double-ended bolts, bolts threaded at one end only may be employed to pull the frame sections together. Thus, each bolt may be headed at one end and threaded at the other; the bolt may be dropped in aligned notches 44 of registering reinforcing strips 35 with the head of the bolt seated against the outside of the leg 37 of one reinforcing strip and with a butterfly nut 51 threaded on the opposite end and seating against the outside of the registering reinforcing strip. By rotating the bolt, then, the two frame sections may be drawn together. Where a single ended bolt is used, obviously, also, the bolt may be threaded directly into the leg 37 of one of the two registering reinforcing strips and this strip need not be notched for reception of the bolt. Other alternatives will readily suggest themselves to those skilled in the art.

After the frame sections are in place, covering strips are placed over the adjacent ends of the sections to conceal the terminal strips 26 thereof, bolts 50, studs 45, etc., and to give the completely assembled frame the appearance of a conventional one-piece casing. Separate covering strips are used for the sides and the top of the frame. The side covering strips are denoted at 55 and the top covering strip at 56 (Figs. 2, 3, 4, 7 and 8).

The side and top covering strips are similar in construction. Each is U-shaped in cross-section and is adapted to be placed over the adjacent ends of the frame sections with its flat part 57 out and its legs 58 extending inwardly and enclosing the terminal strips 26 of the frame sections. The side and top covering strips differ from one another only in that the top covering strip 56 has two parallel slots 59 cut into its flat part 57 from both ends while each side strip 55 has two tongues 60 bent upwardly from its upper end and is unslotted at either end. The tongues 60 of the two side strips 55, respectively, are adapted to engage in the slots 59 at the opposite ends, respectively, of the top strip 56. Corresponding slots 59 at each end of the top strip 56 may be made, as shown in Fig. 7, wide enough to permit adjustment of the frame members without interference.

Spring steel C-clips 65 are welded to the insides of the flat portions 57 of both the side and top covering strips. These engage the opposed surfaces of terminal strips 26 of the frame sections to resiliently but securely hold the covering strips in place.

The top covering strip 56 is first put in place by shoving it over the terminal strips 26 of the top rails 24 of the frame sections 20 and 21. The springs 65 will hold it in place. Then each side covering strip 55 may be put in place by first inserting its tongues 60 into one pair of slots 59 of the top covering strip and then shoving it inwardly to cause its spring clips 65 to engage opposed side surfaces of cooperating terminal strips 26 of the related side rails 22 of the frame sections 20 and 21.

The springs 65 will hold the covering strips in

place, but, if desired, each side covering strip may, in addition, be fastened by a screw 67 to an anchor plate 70 (Figs. 2, 4 and 6) by threading the screw into one leg 71 of the anchor plate. The anchor plates may be fastened to the floor by screws that pass through holes 72 in the plates. The legs 73 of the anchor plates are adapted to abut against the studding 45.

Where the trim of this invention is to be used as a door casing, one frame section, such as section 20, will have hinges 75 secured to it on which the door D (Fig. 3) may be hung. The covering strips 55 and 56 will then serve as a stop, corresponding legs 58 of the side and top covering strips seating against the terminal strips 26 of frame section 20 for this purpose. The covering strips are, of course, made sufficiently wide to allow of any required adjustment of the frame sections while accomplishing their purpose.

In the modification of the invention shown in Figs. 9 and 10, two frame sections and covering strips are employed as in the first described embodiment of the invention, but different means is used for drawing the two frame sections together to clamp them to the partition wall. The frame sections 80 and 81 shown in Figs. 9 and 10 are somewhat different in cross-sectional shape from the frame sections 20 and 21. This simply illustrates that the invention may be used with casings of a wide variety of rolled or stamped shapes and architectural styles.

Each of the frame sections 80 and 81 has a flat side 86, from one end of which the terminal strip 87 projects outwardly and from the other end of which the side wall 88 projects inwardly. The side wall is flared laterally as denoted at 89 and from the flared portion there extends the offset portion 90 which is parallel to the main portion of the side wall but offset therefrom. A flange portion 91 extends at right angles to offset portion 90 of the side wall and a terminal abutting strip 92 extends at right angles to the flange portion.

To the inside surfaces of the side walls 88 of the side rails of the frame sections there are fastened at spaced intervals right angular shaped metal strips 95 which constitute metal jamb hook eyes. One leg of each of these straps is spot-welded, or otherwise secured to the side wall 88 of a frame section. The holes 96 in these hook eyes are adapted to receive the downwardly projecting legs 99 of U-shaped metal hook clamps 100, the legs of each clamp engaging in the holes of registering hook eyes. The insides of the legs 99 of each hook clamp are inclined and diverge downwardly from one another, so that as the hook clamp is driven downwardly in a pair of hook eyes by a hammer, a wedging effect will be obtained and the two frame sections will be pulled together to clamp opposite sides of the partition wall which are denoted at 105 and 106, respectively. The insides of the legs 99 may also be serrated as shown in Fig. 10 to improve the gripping action of these legs on the hook eyes.

After the frame sections have been pulled together so that the strips 92 of top and side rails of the two sections abut against the partition surfaces 105 and 106, nails 107 may if desired be driven into the studding 108 above the hook clamps, as illustrated in Fig. 10, to retain the hook clamps in clamping position. The covering strips 85 are then shoved over the opposed terminal strips 87 of the frame sections to con-

ceal the terminal strips 87, hook clamps, etc., and to give the casing a finished appearance. The covering strips are held in place by spring steel clips 110, similar to the clips 65 used in the first-described embodiment of the invention and spot-welded to the insides of the covering strips. These clips engage opposed surfaces of terminal strips 87 and resiliently but securely hold the covering strips in position. The covering strips 85 serve as a stop when the casing is used as a door frame.

With either embodiment of the invention it will be seen that the trim can be erected after plastering and painting has been done and without damage to either.

Furthermore, with either embodiment of the invention the trim can be removed at any time without damage to the trim or to the walls. The screws at the bottoms of the side rails can be removed; and the screw driver can then be inserted under the edges of each covering strip to pry it off the frame sections. This is a simple task since the covering strips are then only held by spring clips 65 or 110. After the covering strips are removed the bolts 50 can be loosened and lifted out of the notches 44 of the reinforcing strips 35 and the nails 43 drawn in the case of the embodiment shown in Figs. 1 to 8 inclusive, or the nails 107 can be drawn and the hook clamps 100 driven up to release the frame sections in the case of the modification shown in Figs. 9 and 10. In either instance, it is a matter of a few minutes work to remove the trim; and the trim can be salvaged 100%.

If it is desired to change the direction of swing of a door this can be done readily by removing the frame sections from the door opening, reversing them, and reclamping them in the opening. The trim of the present invention, there, is flexible in adaptation, easy to erect or dismantle, and permits of considerable saving in time and cost of erection.

While the invention has been described as applied to metal trim it will be understood that it is by no means confined to such use, since it may be employed on wood or composition trim and frames as well. It will be understood, also, that while the invention has been described in connection with certain specific embodiments thereof, it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A casing for an opening in a wall of a building comprising a pair of opposed frame members which are adapted to embrace opposite faces of the wall around the edge of the opening, each of which has a terminal edge adapted to abut against a face of the wall adjacent the opening, a portion adapted to extend generally parallel to the wall in spaced relation thereto, a portion projecting inwardly from the last-named portion beyond said terminal edge and a terminal edge strip projecting from the last-named portion in a direction away from the face of the wall that bounds said opening and in a direc-

tion generally parallel to the first-named portion the terminal edge strips of the two frame members being parallel and spaced from one another when the frame members are mounted in position, means for drawing the frame members bodily toward one another to clamp them to the wall about the opening, and a covering member which is of U-shape in cross-section and which, when in position, encloses the terminal edge strips of the two frame members with said strips lying within its leg portions and with the inside of one of its leg portions abutting against one of the terminal edge strips, said covering member having flexible straps secured to its inside surface at spaced intervals to engage the opposed faces of said terminal edge strips to hold the covering member resiliently in position.

2. A casing for an opening in the wall of a building comprising a pair of opposed frame members which are adapted to embrace opposite side faces of the wall around the opening, each of which has an edge which is adapted to abut against one side face of the wall, a side portion adapted to extend generally in the direction of a side face of the wall but in spaced relation thereto, a portion which is adapted to extend inwardly of the wall opening beyond said edge, and a terminal edge strip which projects from the last-named portion in a direction away from the wall face bounding said opening, the terminal edge strips of the two frame members being parallel and spaced from one another when the frame members are mounted in position, a plurality of reinforcing members secured in linearly spaced relation to the inside of each frame member, each reinforcing member having a portion which contacts with and reinforces the side portion of the frame member, a portion which extends parallel to the inwardly extending portion of the frame member but is spaced therefrom, a portion perpendicular thereto, and two portions projecting perpendicularly in opposite directions from said perpendicular portion, one of said two last-named portions contacting and reinforcing the inwardly extending portion of the frame member; and the other of said two last-named portions being adapted to seat against the wall face bounding the opening when the frame members are in position, reinforcing members of the two frame members being aligned when the frame members are in position, means engaging aligned reinforcing members of the two frame members to draw the two frame members together, a covering member which encloses the terminal edge strips of the two frame members when in position, and means for resiliently holding the covering member in position.

3. A casing for an opening in the wall of a building comprising a pair of opposed frame members which are adapted to embrace opposite side faces of the wall around the opening, each of which has an edge which is adapted to abut against one side face of the wall, a side portion adapted to extend generally in the direction of a side face of the wall but in spaced relation thereto, a portion which is adapted to extend inwardly of the wall opening beyond said edge, and a terminal edge strip which projects from the last-named portion in a direction away from the wall face bounding said opening, the terminal edge strips of the two frame members being parallel and spaced from one another when the frame members are mounted in position, a plurality of reinforcing members secured in linearly

spaced relation to the inside of each frame member, each reinforcing member having a portion which contacts with and reinforces the side portion of the frame member, a portion which extends parallel to the inwardly extending portion of the frame member but is spaced therefrom, a portion perpendicular thereto, and two portions projecting perpendicularly in opposite directions from said perpendicular portion, one of said two last-named portions contacting and reinforcing the inwardly extending portion of the frame member, and the other of said two last-named portions being adapted to seat against the wall face bounding the opening when the frame members are in position, reinforcing members of the two frame members being aligned when the frame members are in position, means engaging the first-named perpendicular portions of aligned reinforcing members of the two frame members which is manipulable through the space between the terminal edge strips of the two frame members to draw the frame members together to clamp them to the wall, a covering member which covers the space between the terminals edge strips of the two frame members when in position, and means for resiliently holding said covering member in position.

4. A casing for an opening in the wall of a building comprising a pair of opposed frame members which are adapted to embrace opposite side faces of the wall around the opening, each of which has an edge which is adapted to abut against one side face of the wall, a side portion adapted to extend generally in the direction of a side face of the wall but in spaced relation thereto, a portion which is adapted to extend inwardly of the wall opening beyond said edge, and a terminal edge strip which projects from the last-named portion in a direction away from the wall face bounding said opening, the terminal edge strips of the two frame members being parallel and spaced from one another when the frame members are mounted in position, a plurality of reinforcing members secured in linearly spaced relation to the inside of each frame member, each reinforcing member having a portion which contacts with and reinforces the side portion of the frame member, a portion which extends parallel to the inwardly extending portion of the frame member but is spaced therefrom, a portion perpendicular thereto, and two portions projecting perpendicularly in opposite directions from said perpendicular portion, one of said two last-named portions contacting and reinforcing the inwardly extending portion of the frame member, and the other of said two last-named portions being adapted to seat against the wall face bounding the opening when the frame members are in position, reinforcing members of the two frame members being aligned when the frame members are in position, means engaging the first-named perpendicular portions of aligned reinforcing members of the two frame members to draw the frame members together to clamp them to the wall, a covering member which covers the space between the terminal edge strips of the two frame members when in position, and means for resiliently holding the covering member in position, said covering member being U-shaped in cross-section and having one of its leg portions abutting against the outside surface of the terminal strip of one frame member to form a stop for a door hinged to said one frame member.

5. A casing for an opening in a wall of a building comprising a pair of opposed frame members which are adapted to embrace opposite faces of the wall around the edge of the opening, each of said frame members having an edge which is adapted to abut against one side face of the wall, a side portion which is adapted to extend generally in the direction of a side face of the wall, a portion which is adapted to extend inwardly beyond said edge, a terminal edge strip which projects from the last-named portion in a direction away from the wall face bounding said opening and generally parallel to said side portion, and a seating portion which is adapted to seat against the portion of the wall which bounds the opening, a plurality of bolts which have threads of different hands at opposite ends, nuts which engage said threaded portions, said bolts having gripping portions intermediate their ends for manipulating them through the space between registering terminal strips of the frame members, a covering member which, when in position covers the space between the terminal edge strips of the two frame members, and means for resiliently holding the covering member in position.

6. A casing for an opening in a wall of a building comprising a pair of opposed frame members which are adapted to embrace opposite faces of the wall around the edge of the opening, each of said frame members having an edge which is adapted to abut against one side face of the wall, a side portion which extends generally in the direction of the wall opening when the frame members are in position, a portion extending inwardly, and a terminal edge strip which projects from the last-named portion in a direction away from the wall face bounding said opening and generally parallel to said side portion, the terminal edge strips of the two frame members being spaced from one another when the frame members are mounted in position, each frame member having a plurality of hook eyes secured to the inside of its side portion, U-shaped clamping members whose legs are adapted to be engaged in registering hook eyes of the two frame members, said U-shaped clamping members having the insides of their legs diverging from one another toward their ends, a cover-

ing member which encloses the terminal strips of the two frame members when in position, and means for securing the covering member in position.

- 5 7. A casing for an opening in a wall of a building comprising a pair of opposed frame members which are adapted to embrace opposite faces of the wall around the edge of the opening, each of said frame members having a pair of parallel 10 side rails and a connecting top rail and each rail being shaped to have an edge that is adapted to abut against one face of the wall, a side portion which is adapted to extend generally in the direction of said face when the frame members are in position, a portion extending inwardly from the side portion beyond said edge, and a terminal strip projecting from the inwardly extending portion in a direction away from the wall face that bounds said opening and in a direction generally parallel to said side portion, 15 means for drawing the two frame members bodily toward one another to clamp the wall, a covering member for the side rails of the two frame members and a covering member for the top rails of the frame members, each covering member being of U-shape in cross-section and enclosing, when in position, the two terminal strips of the pair of rails with which it is used with one of its legs abutting against one terminal strip so as to serve as a stop, and means for holding the 20 several covering members in position, the top and side covering members having interengaging tongues and slots at their contiguous portions so as to interlock them together.
